UNITED STATES PATENT OFFICE.

CHARLES H. LAND, JR., OF DETROIT, MICHIGAN, ASSIGNOR TO FRUEHAUF TRAILER COMPANY, OF DETROIT, MICHIGAN, A CORPORATION OF MICHIGAN.

SEMITRAILER.

Original No. 1,568,560, dated January 5, 1926, Serial No. 691,342, filed February 8, 1924. Application for reissue filed July 21, 1926. Serial No. 124,080.

This invention relates to semi-trailers. The subject matter of the invention may be classified as follows:

5 Wheels are provided on the trailer frame near the front end for running up the inclined approach to the horizontal tracks on the truck when the truck backs into the trailer, and means are provided for automatically raising these wheels off the horizontal portion of the tracks when the trailer is in its final position on the tractor.

When the tractor backs into the semi-trailer, the latch hooks are automatically positioned to engage with the locking bar on the truck. This is accomplished by the supporting unit swinging from its forward position to a vertical position during the travel on the truck tracks of the wheels on the front end of the trailer frame.

20 The construction of the automatic means for raising the supporting element of the trailer when the truck drives into the trailer involves a new arrangement whereby the actuating connection is near the fulcrum of the swinging supporting element so that only a small amount of movement is required to lift the supporting element even if greater power is required, distance being considered more important here than power which is proportionately large due to the heavy truck.

30 The brake which has been set in position prior to the time when the truck backs into the trailer is automatically released by the truck at the proper time.

35 When the truck starts out from under the trailer, it first draws the legs into position and automatically locks them in this position before the uncoupling movement takes place.

40 Provision is made so that the truck can not uncouple from the trailer until the legs of the supporting elements are locked in their upright position, the uncoupling being prevented prior to the locking of said legs in position but allowed to uncouple subsequently.

45 Mechanism is provided which may be operated from the cab of the truck for blocking an override brake mechanism to permit backing without setting the brakes.

50 The coupling head involves new and novel devices, one of which is an arrangement to release the locking pin located in the cou-

pling head from the strain incident to the momentum of the truck when the locking pin drops into place.

55 There are other features of novelty, but this in a general way summarizes the features to which the claims are directed.

In the drawings:

60 Fig. 1 is a plan view of the trailer and the rear portion of the truck including the fifth wheel. The parts are shown before the truck has been completely uncoupled from the trailer.

65 Fig. 2 is a side elevation of the same parts showing the parts in the same position.

Fig. 3 is a fragmentary longitudinal section of the same parts.

70 Fig. 4 is a longitudinal section through a portion of the fifth wheel on the truck and the coupling head on the trailer.

Fig. 5 is a longitudinal section of the trailer showing the brake operating connections.

75 Fig. 6 is a section taken on the line 6—6 of Fig. 1 showing the tripping lug 17 as it is when the sliding head is in its rearmost position.

Fig. 7 is a section taken on the line 7—7 of Fig. 2.

80 Fig. 7^a is an enlarged view of a portion of Fig. 7.

Fig. 8 is a front elevation of a trailer and the fifth wheel part of the truck, showing the trailer wheels as raised slightly off the track carried by the truck.

85 Fig. 9 is a longitudinal section through the forward part of the trailer when tractor is entirely away showing by dotted lines how the drop of the supporting legs serves to position the latch hooks in the path of the lock bar of the truck, after impact of the bumper loops but before final coupling.

90 Fig. 10 is a front elevation of the coupling head.

Fig. 11 is a plan view of the same.

95 Fig. 12 is a plan view of the trailer similar to Fig. 1, but showing the trailer and the fifth wheel part of the truck after the truck is backed entirely into the trailer.

100 Fig. 13 is a longitudinal section of the trailer and the rear part of the truck parts being omitted for clearness, showing the parts when in position for transport as distinguished from Fig. 3, which shows the parts in the act of coupling.

Fig. 14 is a plan view of the rear of the truck.

Fig. 15 is a detail showing means for setting the brake temporarily in the initial 5 movement of uncoupling.

The apparatus is somewhat difficult to understand and follow due to the large number of relative changes that occur in performing the automatic functions outlined 10 above. It is therefore thought that the easiest way to approach and describe the matter is to describe the operation and the parts together, beginning with the truck backing into the semi-trailer.

15 In the plan view of the back of the truck shown in Fig. 14, will be seen the tracks *a* which are inclined as shown in Figs. 2 and 3, in the manner set forth and claimed in the Pescatore Patent No. 1,084,820. A pair of 20 bumper loops *b* (Figs. 2 and 3) are provided on the front of the trailer for first striking the inclined track and taking the shock on the trailer. As the inclined track backs further it strikes the rollers *c* supported on the 25 bottom of the side sills of the trailer by the brackets *d*. This, of course, greatly facilitates the truck running under the trailer and lifting the same.

Refer to Fig. 9. When the truck has previously uncoupled itself from the trailer, it has left the latch hooks *e* in the raised position shown by the full lines and has the leg props inclined forwardly. However, as soon as the truck raises the trailer off the ground 30 by backing under it, the forwardly inclined legs *f* of the supporting element swing from the full line position shown in Fig. 9 to the dotted line position,—that is, down to the vertical. The legs are connected by the link 35 *g* to the sliding bar *h*. This sliding bar is connected at the front with a coupling head *i* on which are pivoted the two bell crank-like 40 latch hooks *e*. These latch hooks were left held in their lifted position by reason of the tail engaging the lug *j* on the bottom of the bar *k*, which extends from the front cross channel to the first intermediate channel of the trailer frame (Fig. 1; compare also Fig. 11). This backward movement of the sliding bar *h* permits the two latch hooks which 45 are connected by the shaft *m* (Fig. 10) to drop down into the dotted line position shown in Fig. 9. The bill of the latch hook is inclined so that when the lock bar *n*, shown 50 in dotted lines in Fig. 9, strikes the inclined bill it throws the swinging latch upwardly and passes under it and into the gullet of the latch which drops back upon the lock bar by gravity. This is illustrated in Fig. 3. 55 There are two of these lock bars *n* (see Fig. 14). They are supported on the upstanding lugs *o* of the cap plate *p* in the center of the fifth wheel of the truck. This cap plate *p* is shown in Fig. 3 and is the upper cap plate, 60 while the lower cap plate *q* carries the pro-

jecting lugs *r* (Fig. 14) which are four in number, and which slide on the rods *s* that bridge the circular track *t* from front to back. Four spacing springs *u* are coiled about these rods and abut against the projecting lugs *r*. This arrangement gives the two center cap plates a floating action with respect to the larger circular track so that there may be a slight yield and play in the coupling of the trailer to the truck, so as 75 to absorb the shocks.

When we left the truck and trailer, the hooks had dropped over the locking bar end, but the supporting legs are still in their upright position, having swung down to the 80 vertical. Now, it is desirable to automatically lift these legs out of the way and provide an automatic release for the brake when the operation of coupling the truck and trailer is complete. In the normal cycle of 85 operation, the brakes are retained in set position at the end of the uncoupling operation by means of a lever *w*; consequently, it is not necessary under normal conditions to operate the brakes again before coupling. But, 90 in case it is desired to move the detached trailer about without the aid of the truck, the brakes may be released manually. Of course, it will then be necessary to set the brakes by hand before the truck is backed 95 into the trailer. The means for releasing the brakes manually under these conditions and resetting them again comprises a brake rod *u'* that runs to the front of the trailer where it connects with the brake lever *w*, 100 which operates in connection with the usual toothed segment *x* and pawl *y* (see Fig. 1). The brakes shown herein are of the well known band type, a spring 18 being provided to insure quick releasing action.

105 It becomes necessary here-to make a slight digression and describe the coupling head and the sliding element which serves to perform a number of the automatic operations such as lifting the supporting legs and 110 drawing them down into a vertical position, releasing the brake, and some of the other operations. This coupling head is detailed in Fig. 4. The sliding element is the rod *h*. The coupling head is a two-part 115 member comprising the pin-holding casting *z* and the hook-carrying-casting 1. An abutment collar 2, is pinned to the sliding element *h*, and a coiled spring 3 yieldingly spaces the latch-hook-carrying casting 1, and yieldingly forces it against the pin-holding casting *z*. The latter is pinned to the end of the sliding bar *h*. Secured to the pin holding casting *z* of the coupling head is a lever 4, adapted to abut against the lower end of 120 the tapered locking pin 5, when raised. A locking bar 6 extends from the front cross channel bar to the first intermediate cross channel bar of the trailer frame (see also Fig. 1). This has an elongated slot 7, in its 125 130

forward end and a small opening 8 to the rear of this.

When the supporting legs *f* are in their extreme forward position such as shown in Fig. 2, the pin 5 rests in the forward end of this slot 7. The length of the slot permits the movement already referred to and illustrated in Fig. 9, where the legs drop the forward inclined position to the vertical position for the purpose of positioning the latch hooks. In the condition that we left the trailer and truck, the latch hooks had engaged with the lock bar and the trailer and truck were coupled together, but the supporting legs had not been drawn up nor the brakes released. This can only be effected by the travel of the sliding element, coupling head and truck backwardly with respect to the trailer while the trailer remains stationary. But, as we have already seen, these parts are locked against this movement by reason of the pin 5 (Fig. 4) being at this time located in the slot 7. However, the fifth wheel of the truck being coupled up with the coupling head of the trailer, by reason of the latch hooks engaging over the lock bar that is carried by the fifth wheel, the stud 10 is directly under the lever 4. This stud 10 passes through the center of the fifth wheel. Its lower end is enlarged and slotted as at 11, and this slot is connected with a lever 12 of the bell crank type, which is connected by the rod 13 with the driver's cab, not shown. By pulling forward on this rod 13, the lower arm of the lever is raised. This raises the stud 10 and the lever 4, which encounters the lower end of the tapered locking pin and thrusts it up against the force of the spring 14. The upper edges of both the holes 7 and 8 in the lock bar are beveled off as shown in Fig. 4. This lever 4 rises to the dotted line position shown in Fig. 4, and lifts the pin to the dotted line position shown in Fig. 4, but bear in mind the whole coupling head and pin are now in the elongated slot 7. This releases the sliding elements of the trailer, to wit: the coupling head and the sliding bar, so that they are free now to move relatively backward with respect to the trailer to accomplish the results now to be described.

The driver of the truck now backs up the truck slightly. The truck together with the sliding elements on the trailer move backwardly. The tapered end of the locking pin in connection with the beveled edge of the slots serving to cause the locking pin to climb out of the slot. The parts continue their relative movement along locking bar until the opening 8 of the locking bar is reached by the locking pin 5. When it registers with this opening, the helical spring 14 causes it to shoot into this opening. If this were to immediately arrest the truck, the pin would likely shear, but this is nicely taken care of by the inertia resisting arrangement afforded

by the making of the coupling head in two pieces, carrying the pin on the casting *z* and the coupling hooks on the casting *I*. The consequence is that the coil spring 3 allows these two parts of the coupling head to separate slightly so that the inertia of the truck may be stopped by the spring 3 in a gradual fashion rather than by being suddenly arrested by the pin 5. In short, this constitutes a nicely arranged spring buffer in the coupler to prevent the shearing of the pin 5.

This relative movement of the sliding elements on the trailer accomplishes these results: it forces the sliding bar *h* to the rear. Refer to Fig. 3. The sliding bar is connected by the link *g* with the supporting legs *f*. This connection is made as close to the fulcrum of the legs as possible so that a minimum amount of travel of the bar *h* will be required to swing the legs up to their folded position, such as shown in Fig. 13. This is one result. The second result is that the sliding bar *h* releases the brakes, it being remembered that these were set manually by the lever *w* before the truck was backed under the trailer. Referring to Figs. 5, 6, 7 and 15, the brake rod *u* connecting the brakes with the lever *w* is divided into front and rear sections arranged to be connected by a toothed portion 15 on the rear section normally engaged by a projection 15^a in the front section (see Fig. 5). On the stationary bar *k* is supported a brake releasing lever 16 having an eye 16^a through which the forward section of the brake rod extends. At its rear end, this lever has an offset lug 16^b positioned in the path of tripping lug 17 carried by the coupling head. As the coupling head reaches its rearward limit of travel during coupling, the lug 17 will strike the lug 16^b 105 and lift the projection 15^a upwardly out of engagement with the toothed portion 15 (see Fig. 6), thereby disconnecting the brake rod sections. By this time a brake control cam 40 on the slidable rod *H* (see Fig. 15) will 110 have moved into its rearmost position out of operative engagement with an arm 25 on the brake rock shaft 26. The spring 18 immediately forces the brake rod forwardly which releases the brakes, the truck and trailer being at this time coupled together 115 and ready for combined operation.

A third result accomplished by the backward sliding movement of the sliding elements of the trailer is to disengage the rollers *c* from the tracks so as to give a slight clearance to provide a free movement of the rollers 19 (Fig. 8) on the fifth wheel track *t*. These rollers 19 are near the ends of the lock shafts *n* (Fig. 14). Secured to the inside of 125 the side channel sills of the trailer are the U brackets 20 (Figs. 1, 3 and 7). These brackets are adapted to straddle the rollers 21 on the extreme ends of the lock bars *n*. When these sliding elements reach the rear 130

of their movement these rollers strike the inclined face 22 (Fig. 3) of this U bracket and this serves to raise the trailer frame just slightly with respect to the truck. This lifts 5 the rollers *c* off the track just sufficiently as shown in Fig. 8 so as to clear the same. The rollers 21 and the U brackets are shown inter-engaged in Fig. 12.

This completes the coupling and automatic 10 operation of the devices making the truck and trailer ready for transit. It may, however, be mentioned that the brake is also arranged to be applied when the trailer attempts to override the truck. The forward 15 end of the rear portion of the brake rod *u* is offset as shown in Fig. 12 to provide an abutment 23, which is adapted to strike the shoulder 24 on the coupling head 1 in case the truck is suddenly slowed or stopped or the 20 trailer suddenly accelerated, the spring 3 permitting this override action. This is a very useful function in stopping, as then of course the application of the brakes to the truck leaves the trailer perfectly free to continue on were it not for this brake. This 25 override braking arrangement hence provides suitable brakes to stop the trailer coincidentally with the application of the brakes to the truck.

30 We now turn to the uncoupling of the truck from the trailer. The truck driver pulls on the rod 13 (Fig. 4). This raises the stud 10, the lever 4, and in turn raises the locking pin 5 to its uppermost position shown 35 in the dotted lines of this figure. The driver then starts the truck forward, which pulls the coupling head and bar *h* forwardly. In such movement the lug 17 permits the forward section of the brake rod *u*' to fall down 40 into engagement with the forwardly inclined teeth on the part 15, and shortly thereafter the forward end of a cam 40 (see Fig. 15) carried by the rod *h* strikes an arm 25 on the brake rock shaft 26 thereby moving the rear 45 section of the brake rod *u*' rearwardly while the forward section remains in its set position. Thus, the brakes will be set automatically during the initial movement of the head 50 during uncoupling, and further movement of the head will carry the cam 40 forwardly so that its rear end will pass out of engagement with the arm 25. When this occurs the lever *w* acting through the part 15^a and the segment 15 will become effective to hold the 55 brakes in the set position into which the cam 40 has moved them. It will be remembered that the lever *w* was moved into or retained in brake setting position prior to the coupling of the truck and trailer and that this lever 60 together with the forward section of the brake rod *u*' has been retained in brake setting position by the pawl and rack *y* and *x* during normal coupling and uncoupling operations. If it is now desired to release the 65 brakes so as to permit the detached trailer

to be moved about without the aid of the truck, the lever *w* which is now acting to hold the brake set may be released manually.

The sliding elements, to wit: the sliding bar *h* and the coupling head on the trailer, 70 now move forward relatively with respect to the trailer which remains stationary. The lock pin 5 by reason of its tapered lower end, climbs out of the hole 8 and rides along the locking bar until it drops in the elongated 75 slot 7 in the bar (Fig. 4). In making this relative travel forward, the sliding elements accomplish several results. One result is to automatically uncouple the latch hooks from the lock bar,—in short, uncouple the 80 trailer from the truck. Referring to Fig. 9, it will be seen how this is accomplished. As the hooks move forward with the sliding coupling head the tails 27 strike the lug *j* on the bar *k* (see also Fig. 11); this kicks the 85 hooks up as shown in the full lines in Fig. 9, thereby permitting the locking bars *n* to draw away. A second result accomplished by the 90 relative travel of the sliding elements forward on the trailer is to pull the legs downwardly, as these are directly tied to the sliding bar *h* by the links *g*.

By comparing the different parts in Fig. 9, it will be apparent that the hooks are not kicked off the locking bars until the legs 95 have gone beyond a perpendicular position. It is only in the final travel from the perpendicular position to the slightly inclined forward final position that the hooks are thrown from the locking bars. This travel takes 100 place by reason of the elongated slot 7 (see Fig. 4), that is,—the pin 5 drops into the rear of this slot and hence absolutely prevents the legs from folding up before the hooks are kicked off the lock bars. This absolutely prevents any accident as for instance, the legs dropping back or folding up slightly so that when the truck draws away from the tractor, the forward end of the trailer would fall. This cannot happen, as it is only by 105 the slight amount of movement allowed by the elongated slot that the hooks are kicked off. To further prevent any accidental throwing of the hooks by any other force, it will be seen from referring to Fig. 11 that 110 one of the hooks is provided with an upwardly projecting lug 29. This is adapted to ride along the underside of the bar *k* so that these hooks can only be released when they are in their forward position opposite 115 the slot 30, in the bar *k*.

Oftentimes it is desirable to back the truck and trailer. However, this would always apply the override brake except for the arrangement I have provided for blocking off the 120 override brake on these occasions. The operator of the car need simply thrust back on the rod 13. This carries the lever 12, (Fig. 4) to the lowermost position shown in this figure. This pulls down the stud 10, which has a col- 125

lar 31, which engages the tail 32 of the lever 33 and throws this lever up against the under side of the lock bars 6, so that the same is in the path of the lug 34. This provides the inner fifth wheel parts only a slight movement with respect to the outer wheel and consequently not enough movement so that the shoulder 24 can strike the abutment 23 on the brake rod to apply the brakes.

10 A feature of this trailer and truck to which I desire to call attention is that there is no draft through the coupling device that is operated from the cab and which locks the sliding elements of the trailer in either forward 15 or rear position. The draft is entirely through the locking member on the truck and the latching hooks on the trailer, and these are automatically controlled by the relative movement of the sliding parts of the trailer 20 with respect to the trailer itself.

I claim as my invention:

1. In a truck and a semi-trailer, the combination of a truck provided with inclined tracks at the back, a semi-trailer frame, rollers supported on the trailer frame adapted to run up the tracks, lock bars on the truck having rollers at the ends, and U brackets depending from the trailer frame arranged to engage the rollers on the ends of the locking bars to slightly raise the trailer with respect to the truck when the truck backs clear into the trailer for the purpose of causing the rollers to clear the track.

2. In a truck and a semi-trailer, the combination of a truck provided with a locking member, a trailer frame, a sliding reach and a slideable coupling connected together and supported on the trailer frame, the latter provided with means for engaging the locking member, a swinging supporting element supported by the trailer frame, and a connection between the supporting unit and the sliding reach connecting with the supporting unit relatively close to the fulcrum.

3. In a truck and a semi-trailer, the combination of a truck provided with a locking member, a trailer frame, a sliding coupling head provided with a latching member adapted to engage the locking member on the truck, a sliding reach connected with the coupling member, a swinging supporting unit pivoted on the trailer frame, a sliding member slideable in the trailer frame and connected with the lower end of the supporting unit to act as a tension member, and a connecting link between the sliding reach and the supporting unit near its fulcrum.

4. In a truck and a semi-trailer, the combination of a truck provided with a locking member, a semi-trailer frame provided with a latching member adapted to engage the locking member on the truck but which is left out of the path of the locking member when the truck is uncoupled from the trailer, and means automatically operated for throwing the latch

back into the path of the locking member when the truck backs into the trailer.

5. In a truck and a semi-trailer, the combination of a truck provided with a locking member, a semi-trailer frame provided with a latching member adapted to engage the locking member on the truck but which is left out of the path of the locking member when the truck is uncoupled from the trailer, and means automatically operated for throwing the latch 75 back into the path of the locking member when the truck backs into the trailer operating by means of the truck lifting the trailer.

6. In a truck and a semi-trailer, the combination of a truck provided with a locking member, a trailer frame provided with a stop, a latching member on the trailer frame ordinarily left in a raised position out of the path of the locking member when the truck is uncoupled from the trailer, a sliding element in 80 the trailer, a swinging supporting unit pivoted on the trailer frame and connected with the sliding element, the said swinging supporting element when in a supporting position being somewhat forward of a vertical position, the said latching member being held in its raised position by abutting against the stop and being also connected with the sliding element whereby when the truck backs into the trailer and raises the trailer, the swinging supporting element swings to the vertical, pulls the sliding element and the latch out of engagement with the stop and permits the latch to 85 drop into the path of the locking member of the truck.

7. In a truck and a semi-trailer, the combination of a truck provided with a locking member, a trailer frame, a swinging gravity latch in the form of a hook having an inclined face bill, said hook arranged to slide on the trailer, a stop by which said hook is kicked up to its release position, a swinging supporting member occupying a position somewhat inclined to the vertical forward of a vertical line through its fulcrum when the same is acting as a support for the trailer frame, and connections between said swinging supporting member and the slidably mounted hook whereby when the truck drives under the trailer and raises the same the supporting unit swings to the vertical and draws the hook away from the stop and allows the same to fall into the path of the oncoming locking member.

8. In a truck and semi-trailer, the combination of a truck provided with a locking member, a trailer frame, and a two-part coupling member provided with means for engaging the locking member, the two-part coupling member having the parts yieldably separable, and means for arresting one of the coupling members in a sliding movement that both have with respect to the trailer frame whereby the other part of the coupling member in its yielding separating action may ab-

sorb the inertia shock in arresting the relative movement.

9. In a truck and semi-trailer, the combination of a truck provided with a locking member, a trailer frame, a two-part slidable coupling having a relative sliding movement on the trailer frame, one of the parts provided with means for coupling onto the locking member of the truck, a yieldable connection 10 between the two parts, the other parts provided with a locking pin, and means for arresting the locking pin whereby the arresting of the locking pin part of the coupling permits the other part of the coupling to separate slightly and absorb the inertia shock in 15 arresting the relative movement of the coupling with respect to the trailer.

10. In a truck and semi-trailer, the combination of a truck provided with a locking member, a trailer frame, a locking bar provided with an opening therein, a two-part coupling slidable along the locking bar, the two parts being held together by a spring, a locking pin on the forward part of the coupling head and a latching member secured on the rear part of the coupling head, said locking pin dropping into the opening in the locking bar when it registers therewith while the inertia of the truck and the other part of the 30 coupling is absorbed by the springs when the yielding separation takes place between the two coupler parts when the shooting of the pin into the hole arrests one part of the coupler.

11. In a truck and semi-trailer, the combination of a trailer frame, a locking bar supported thereon with an opening at the rear and an elongated opening in the front, a sliding coupling head slidable with respect 40 to the trailer frame, a supporting unit raised or lowered by the sliding action of the coupler, the coupler provided with a latching member arranged to be automatically released as the sliding coupler nears the completion of its forward relative movement with respect to the trailer frame, and a locking pin on the coupler arranged to engage in the rear opening of the lock bar to hold the supporting unit in its inoperative position and 50 dropping into the elongated slot to lock the supporting unit in its operative position but permitting slight further relative movement forward for the purpose of permitting the latching member to be automatically disengaged.

12. In a truck and a semi-trailer, the combination of a trailer frame, a coupler head slidable thereon provided with a latching hook having a tail on one end, and a trip plug 60 on the trailer frame for engaging the tail of the latch hook to throw the same for automatically releasing the hook when the coupler travels forward with respect to the trailer.

13. In a truck and a semi-trailer, the com-

bination of a trailer frame, a sliding coupler head provided with a latching member, locking means for locking the same with respect to the trailer in its forward position and in its rear position in the sliding movement, the locking means in the forward position permitting however a certain lost motion forward but no movement backward, a trip on the trailer, said latch member striking the trip to throw the latching member to a releasing position after the forward position of the locking means sets the coupler against any backward movement but permits motion forward, and a supporting unit raised and lowered by the relative movement of the coupler head, locked in its upright position when the forward position of the locking means locks against backward sliding movement of the coupler.

14. In a truck and a semi-trailer, the combination of a truck provided with a fifth wheel carrying a locking member, a trailer frame, a coupler head slidable thereon, to effect certain operations, a locking element on the trailer frame, said coupler provided with a latching member arranged to engage the locking element in the forward and rear ends of its sliding movement, and a control member running up through the fifth wheel on the truck for disengaging the interlock between the coupler head and the locking element on the trailer.

15. In a truck and a semi-trailer, the combination of a truck provided with a fifth wheel, a trailer frame, a coupler head slideable longitudinally on the trailer frame to perform certain automatic operations, a locking bar provided with two openings for locking the coupler head at the forward and rear end of its movement, a locking pin for engaging in said openings, and a control member running up through the center of the fifth wheel for disengaging the locking pin from the opening in the lock bar when this is desired.

16. In a truck and a semi-trailer, the combination of a truck provided with a fifth wheel, a trailer frame, a locking bar provided with two openings, a slidable coupler head whose sliding movement serves to perform certain automatic operations, a pin in the coupling head for engaging in the openings to lock the coupling head in the forward or rear end of its movement, a lever on the coupling head, and a stud operating through the center of the fifth wheel which may engage the lever which is thereby swung to disengage the pin from the opening in the locking bar.

17. In a truck and a semi-trailer, the combination of a truck provided with a fifth wheel, a trailer, a sliding coupler head whose sliding movement controls certain automatic operations, means for locking the same at the forward or rear end of its movement, over-

ride brake mechanism on the trailer frame automatically operated when the trailer moves forward with respect to the truck, means for blocking such overriding action to 5 prevent the action of the override brake, and means passing up through the fifth wheel of the truck which may be used both to disengage the locking means of the coupler head or optionally to throw in the blocking mechanism to prevent the operation of the override brake.

18. In a truck and a semi-trailer, the combination of a truck provided with a fifth wheel, a trailer frame, a sliding coupling head slidable on the trailer frame to perform certain automatic operations, means for locking the same at the rear and front of its movement, an override brake mechanism on the trailer operated to apply the brakes when 15 the trailer overrides the truck, a stop supported on the trailer, a lever carried by the coupler head, and means passing up through the fifth wheel of the truck which may be optionally operated to disengage the locking 20 means of the coupler head or throw the lever into the path of the stop to block the overriding of the trailer on the truck and thus prevent the operation of the overriding 25 brake.

19. In a truck and a semi-trailer, the combination of a truck provided with a fifth wheel, a trailer frame, a movable coupling head longitudinal of the trailer frame to perform certain automatic operations, a locking bar provided with a pair of openings and along which the coupler head moves, a locking pin carried by the coupler head and adapted to drop into said openings, a stop on the locking bar, a lever on the coupler, and a stud running up through the center of the fifth wheel which may be raised to 30 disengage the locking pin from the locking bar opening and may be lowered to throw the lever into the path of the stop, and a overriding 35 brake mechanism operated by the overriding of the trailer frame on the truck, said brake being blocked when the said lever is thrown up into the path of the stop to prevent overriding.

20. In a truck and a semi-trailer, the combination of a truck provided with a fifth wheel, a trailer having a yieldable connection through such fifth wheel of the truck, override brake mechanism operated by said 40 trailer moving forward on such yieldable connection with respect to the truck, means for blocking such overriding action, and a control device therefor running through the center of the fifth wheel.

21. In a truck and a semi-trailer, the combination of a truck provided with a fifth wheel, a trailer having a yieldable connection with the truck through the fifth wheel, override brake mechanism on the trailer, a stop 45 member on the trailer, a lever pivoted on the

trailer which can be thrown into the path of the stop to prevent overriding action of the trailer on the truck, and a stud passing through the center of the fifth wheel by which the lever may be controlled to block said overriding action and render ineffective the overriding brakes. 70

22. A vehicle having, in combination, a trailer, a truck adapted to be coupled to the trailer by backing into it, a brake on the trailer, means for holding said brake in set position during coupling of the truck and trailer including two parts having toothed engagement between them, and means actuated in the final movement of the truck during coupling to break the connection between 75 said parts. 80

23. In a truck and a semi-trailer, the combination of a truck, a trailer which is coupled with the truck when the truck backs into the trailer, brake mechanism on the trailer including two brake rod portions connected by a toothed segment and a toothed engagement, and means operated at the finish of the movement of the truck into the trailer for 85 throwing the tooth out of the toothed segment to release the brakes. 90

24. In a truck and a semi-trailer, the combination of a truck, a trailer that is coupled to the truck when the truck backs into the trailer, brake mechanism on the trailer including a severable connection, and a sliding member on the trailer operated by the movement of the truck backward into the trailer for disengaging said severable connection to 95 release the brakes as the truck reaches the end 100 of its movement into the trailer.

25. In a truck and a semi-trailer, the combination of a truck, a trailer which is coupled with the truck when the truck backs into the same, brake mechanism on the trailer including a severable rod in two parts, one part of which runs through a lever with an eye, and a sliding member operated with the movement of the truck and located on the trailer 105 adapted to engage under the lever to lift the same and break the severable connection 110 to release the brakes.

26. In a truck and a semi-trailer, the combination of a truck provided with a locking member, a trailer frame, a coupling head having a sliding movement along the trailer frame to perform certain automatic operations, said coupler head provided with a latching member engaging with the locking member on the truck to couple it together, and means for automatically disengaging the latching member from the locking member when the coupling head approaches the extreme front of its movement. 115 120

27. In a truck and a semi-trailer, the combination of a truck provided with a locking member, a trailer frame, a sliding coupling head on the trailer frame which performs certain automatic operations by its sliding move- 125 130

- ment, a latching member on the coupler head in the form of a bell-crank hook, and a trip lug supported by the trailer frame, adapted to engage the tail of the bell crank hook 5 when the coupling head nears the forward end of its slide to release the hook from the locking member on the truck.
28. In a truck and a semi-trailer, the combination of a truck provided with a locking member, a trailer frame, a sliding coupling head on the trailer frame whose sliding movement performs certain operations, a latching member on the coupling head engaging the locking member and automatically released 10 when it reaches the front of the end of the sliding movement of the coupling, and means for guarding against its release until the front end of the movement of the coupler head is reached.
29. In a truck and a semi-trailer, the combination of a truck provided with a locking member, a trailer, a coupling head slideable on the trailer to perform certain operations, a latching member carried on the coupler 15 head, a bar supported by the trailer frame along the path of movement of the latch, and a trip supported by the bar to disengage the latch from the locking member.
30. In a truck and a semi-trailer, the combination of a truck provided with a locking member, a trailer, a coupling head slideable on the trailer to perform certain operations, a latching member carried on the coupler head, a bar supported by the trailer frame along the 20 path of movement of the latch, and a trip supported by the bar to disengage the latch from the locking member, said bar serving to hold the latch in engagement with the locking member until the latch reaches the forward end of its travel on the coupling head, the bar being provided at this point with an opening to allow the latch to release itself from the locking member.
31. In a truck and a semi-trailer, the combination of a truck, a trailer which may be coupled with the truck when the truck backs into the trailer, having sliding elements arranged to automatically uncouple the draft connections when the lock on these sliding 25 elements is released, brakes on the trailer, and means for first automatically setting the brakes when the truck drives forward with respect to the trailer preliminary to automatically uncoupling the draft connections.
32. In a truck and a semi-trailer, the combination of a truck, a trailer which may be coupled with the truck when the truck drives into the trailer and provided with sliding elements including the coupling head on the 30 trailer for performing certain operations and for uncoupling the draft connections between the trailer and the truck at the forward end of the sliding movement of the coupling head, a brake on the trailer, and means whereby the movement forward of the sliding ele-

ments on the trailer first automatically sets the brakes to permit the uncoupling of the draft connections.

33. In a truck and a semi-trailer, the combination of a truck, a trailer coupled to the truck when the truck backs into the trailer, a sliding coupling head on the trailer slideable to perform certain operations, means for locking the sliding coupler head at the forward end of its sliding movement, a brake 75 on the trailer, and means tripped by the sliding elements on the trailer to apply the brake when the sliding elements move forward, the said movement forward of the sliding elements serving to first set said brakes and then 80 to automatically uncouple the draft connections between the trailer and the truck at the forward end of the sliding movement.

34. In a truck and a semi-trailer, the combination of a truck, a trailer, a coupling member provided with two parts which have relative movement and which are connected one to the truck and one to the trailer, an override brake in the trailer arranged to engage against the coupling part attached to the truck when the trailer tends to override the truck whereby the coupling parts separate and apply the brakes.

35. In a combined vehicle of the character described, comprising a truck and a trailer, 95 the combination of trailer brakes, brake controlling means, mechanism for coupling the truck and trailer together including a member mounted on the trailer and movable in opposite directions upon relative movement between the truck and trailer during coupling and uncoupling, and means to lock said coupling mechanism in coupled position, said member being arranged to control the operation of said locking means and said brake 100 controlling means approximately at the completion of the movement of said member in one direction whereby to release said brakes and to lock said coupling mechanism.

36. In a combined vehicle of the character described, comprising a truck and a trailer, the combination of coupling mechanism including an element mounted on the trailer to move back and forth during coupling and uncoupling of the truck and trailer, means 110 operable to lock said element in the trailer frame at the completion of its coupling stroke, brakes for the trailer, manually operable brake-setting means, and trip means arranged to be actuated by said element approximately simultaneously with the operation of said locking means thereby rendering said brake-setting means ineffectual as a means for holding the brakes in set position.

37. In a combined vehicle of the character described, comprising a truck and trailer, the combination of trailer-brake-controlling means, coupling mechanism for attaching the trailer to the truck including an element 115 mounted on the trailer to move back and forth 120

- in the operation of coupling and uncoupling the truck and trailer, means controlled by said element for automatically locking said element to the trailer approximately at one end of the movement of said element, and means for actuating said trailer-brake-controlling means to release the brakes approximately simultaneously with the operation of said locking means.
- 10 38. In a combined vehicle of the character described, comprising a truck and a trailer, the combination of an element mounted on the trailer to be moved back and forth during the operation of coupling and uncoupling the truck and trailer, brakes for the trailer, manually operable means by which said brakes may be set, and means automatically operable by said element for rendering said manually operable means ineffectual and thereby releasing the brakes approximately at one end of the movement of said element.
- 15 39. A combined truck and trailer vehicle of the character described comprising, in combination, trailer brakes, brake-operating mechanism by which the brakes may be set, an element on the trailer arranged to be automatically moved in the operation of coupling or uncoupling the truck and trailer, and means automatically operable in the movement of said element for acting on said brake-operating mechanism to permit one portion of said brake-operating mechanism to move the brake-releasing position without affecting the brake-setting position of the other portion of said operating mechanism.
- 20 40. The combination with a truck and a trailer, of brakes for the trailer, operating means therefor, means providing an operative connection between said brakes and operating means, a trip device operable to break said connection to release said brakes, and means rendered active by relative movement between the truck and trailer during coupling to operate said trip device.
- 25 41. The combination with a trailer and a truck adapted to be coupled together for combined operation, of brakes for the trailer, manually operable means for setting said brakes, a device mounted on the trailer to move in opposite directions during coupling and uncoupling, and means actuated by said device near one end of its movement for rendering said setting means ineffectual.
- 30 42. The combination with a truck and trailer, of brakes for the trailer, means for setting said brakes and retaining them in set position during coupling of the truck and trailer, and means controlled by relative movement between the truck and trailer during coupling to render said setting means ineffectual.
- 35 43. The combination with a truck and trailer arranged to be coupled together for combined operation, of brake means for the trailer, manually controlled means adapted to set said brake means and hold it in set position, and means operable automatically upon coupling of the truck and trailer for releasing said brake means while said setting means remains in active position.
- 40 44. The combination with a trailer, of brakes therefor, brake control mechanism, means arranged to act on said mechanism to release said brakes automatically, and manually operable means for setting said brakes and simultaneously conditioning said mechanism for automatic operation thereof by said releasing means, said setting means serving to hold said brakes in set position until the operation of said releasing means.
- 45 45. A vehicle having, in combination, a trailer, a truck adapted to be connected to the trailer, a brake for the trailer, means for holding said brake in set position during coupling of the truck and trailer, means providing an operative connection between said brake and said holding means including a clutch device having two interengageable parts, and means operated by relative movement between the truck and trailer to disengage said parts thereby breaking the connection between the brakes and said holding means.
- 50 46. In a combined vehicle of the character described comprising a truck and a trailer, the combination of a device to be operated, manually controlled operating means normally having a mechanical connection with said device for operating the same, a member mounted to slide back and forth on the trailer and arranged to be actuated as the tractor moves relative to the trailer in the operation of coupling to the trailer, and means operated by said member during its coupling stroke to break the connection between said device and said operating means whereby to permit operation of the said device independently of said manually controlled means.
- 55 47. A combined vehicle of the character described comprising, in combination, a tractor, a trailer, a carriage mounted on the trailer to move back and forth during coupling and uncoupling of the tractor and trailer, a coupling device on said carriage, a coupling device on said tractor, said coupling devices being arranged for interengagement near the beginning of the coupling operation and for automatic disengagement near the end of the uncoupling operation, and means for locking said carriage against movement relative to the trailer.
- 60 48. A trailer carrying coupling means which is shiftable forward and back along the trailer, and means to permit the opening of the coupling means at the forward end of its shifting movement and for closing the coupling means as the latter moves rearwardly from its forward position.
- 65 49. The combination of a tractor having a

coupling element at its rear end, a semi-trailer having coupling means mounted on its forward portion and arranged to be slid forwardly and rearwardly by the tractor, means for locking the coupling means in its rear position, and means for holding the coupling means closed in any position other than its forward position and for permitting opening of the coupling means when in its forward position and allowing escape therefrom of said coupling element on the tractor.

50. The combination of a tractor having a coupling element at its rear end, a semi-trailer, coupling means movably mounted on the forward portion of the semi-trailer and arranged to engage said element on the tractor and be moved forward and back thereby, means for locking said coupling means in its rearmost position, means for locking said coupling means in its foremost position, and means for holding said coupling means in operative condition except when in its foremost position and for permitting movement of the said coupling means when in its foremost position to allow escape of said coupling element therefrom, the said means for locking said coupling means in its foremost position operating automatically to effect a lock and being operable to release the lock effect and permit rearward travel of the coupling means when the tractor backs under the trailer.

51. A combined vehicle of the character described comprising, in combination, a tractor, a trailer, a carriage slidably mounted on the forward end of the trailer, a coupling member on the tractor, means on said carriage for engaging said coupling member whereby said carriage will be pulled forward by the tractor in uncoupling from the trailer, and means operating automatically near the end of the uncoupling operation to free said coupling member.

52. A combined vehicle of the character described comprising, in combination, a tractor, a trailer, a movable member on the trailer for supporting the forward end of the trailer when detached from the tractor, a movable element on the trailer operatively associated with said support, two coupling devices one carried by the tractor and the other by said element, said devices being arranged for engagement as the tractor is backed under the trailer whereby to connect said element to the tractor and for disengagement automatically when said member reaches its forward limit of travel during uncoupling of the tractor and trailer, and means to hold said element against movement on the trailer during combined operation of the tractor and trailer.

53. A combined vehicle of the character described comprising, in combination, a tractor, a trailer, a carriage mounted on the trailer to move back and forth during coupling and uncoupling respectively, and coupling means

on said carriage operable automatically during coupling and uncoupling respectively to connect and disconnect said tractor and said carriage.

54. A combined vehicle of the character described comprising, in combination, a tractor, a trailer, an element movably mounted on the trailer, means providing a connection between said element and the tractor while the tractor is being uncoupled from the trailer, the power of the tractor being thereby applied positively to actuate said element, and means operating automatically near the end of the uncoupling operation for rendering said connecting means ineffective.

55. A combined vehicle of the character described comprising, in combination, a tractor, a trailer, an element movably mounted on the trailer and arranged to be connected to the tractor, means operating to maintain a connection between the tractor and said element while the tractor is being detached from the trailer and then to disconnect the tractor and said element automatically near the end of the detaching operation.

56. A combined vehicle of the character described comprising, in combination, a tractor, a trailer, an element movably mounted on the trailer, means for connecting said element and the tractor so that the element will be moved by the tractor while the tractor is being detached from the trailer, and means operating on said connecting means to maintain the connection between the tractor and said element during the major portion of the uncoupling operation and to automatically release said connecting means.

57. A combined vehicle of the character described comprising, in combination, a tractor, a trailer, an element movably mounted on the trailer, a support for the trailer operatively associated with said element, means for connecting said element to the tractor, and cam means acting on said connecting means during uncoupling of the tractor and trailer to maintain an engagement between said element and the tractor until said support has been moved into active position and then to render said connecting means ineffective.

58. A combined vehicle of the character described comprising, in combination, a tractor, a trailer, an element movably mounted on the trailer, a member carried by the trailer and operatively associated with said element, said member being arranged to be moved into a position to support the trailer when detached from the tractor, means to connect said element to the tractor whereby the power of the tractor will be applied positively to move said member into supporting position, and means operating automatically after said member has reached its supporting position to release said connecting means.

thereby freeing said tractor from said element.

59. A combined vehicle of the character described comprising, in combination, a tractor, a trailer, coupling mechanism through which the tractive force of the tractor is applied to the trailer for drawing the same, said mechanism including a head movable back and forth on the trailer frame in 10 the relative longitudinal movement between the tractor and trailer during coupling and uncoupling respectively, locking means by which said head is rigidly connected to a part on the tractor near the beginning of 15 the coupling operation and automatically disconnected therefrom near the end of the uncoupling operation, a second locking means by which the head is rigidly connected to the trailer frame at the end of its coupling 20 stroke, a land-engaging member for supporting the forward end of the trailer when detached from the tractor, said member being mounted on the trailer and movable between supporting and non-supporting positions, 25 and connecting means between said head and said member operable to pull said member into active position in the movement of said head during its uncoupling stroke.

60. A combined vehicle of the character described comprising, in combination, a tractor, a trailer, a head mounted on the trailer to move rearwardly during coupling and forwardly during uncoupling of the tractor and trailer, a movable supporting 35 member on the trailer operatively associated with said head so as to be moved out of and into land-engaging position during the coupling and uncoupling strokes of said head respectively, inter-engageable coupling devices 40 one on the tractor and the other on said head adapted to provide a rigid connection between the tractor and the head, stationary cam means on the trailer operable in the movement of said head to maintain engagement between said devices during the uncoupling stroke of said head until said member has been moved into supporting position and then to permit disengagement of said devices whereby to free the tractor from the trailer, 45 and means for locking said head in its rear-most or coupled position.

61. In a combined vehicle of the character described comprising a tractor and a trailer, a coupling mechanism comprising, in combination, a coupling device on the tractor, a coupling device movably mounted on the trailer and adapted for engagement with said tractor coupling device, means for actuating said trailer coupling device automatically to 55 cause it to engage and disengage said tractor device at the beginning of the coupling operation and at the end of the uncoupling operation respectively including a head operatively connected with said trailer coupling device 60 and adapted to be reciprocated back and forth

on the trailer as the tractor moves toward and away from the trailer during coupling and uncoupling and in such reciprocation to actuate said trailer coupling device, and locking means operable to hold said head in its 70 rearward or coupled position so that the tractive force of the tractor may be applied to the trailer through the medium of said coupling devices and said head.

62. The combination with a tractor and a semi-trailer arranged for automatic connection and disconnection, of brakes for the semi-trailer, a brake operating element on the trailer, a separate movable element which is movable into and out of cooperating relation 80 with the brake operating element, and a trip device arranged for engagement with the movable element which effects movement of said element upon relative movement of the tractor and trailer in the action of disconnecting, so that the movable element engages the said brake operating element to hold the 85 brakes applied independently of the trip device, while the tractor and semi-trailer remain disconnected.

63. The combination with a tractor and a semi-trailer arranged for automatic connection and disconnection, of brakes for the semi-trailer, brake operating mechanism including two parts, one of which is connected to the brakes and the second of which is separate from the first and movable into and out of holding position as regards the first part, and means for moving the said second part into and out of holding position upon relative movement between the truck and trailer as they disconnect and connect respectively, whereby the brakes are held applied while the semi-trailer is disconnected and released when the semi-trailer is connected to the 105 tractor.

64. The combination with a tractor and a semi-trailer arranged for automatic connection and disconnection, of brakes for the semi-trailer, brake operating mechanism including two parts, one of which is connected to the brakes and the second of which is separate from the first and movable into and out of holding position as regards the first part, a trip device arranged for contact with the 110 second part for effecting movement of the said second part into holding position as regards the first part upon relative movement between the tractor and trailer during the disconnecting action to hold the brakes applied 115 while the semi-trailer is disconnected from the tractor.

65. The combination with a tractor and a semi-trailer arranged for automatic connection and disconnection, of brakes for the semi-trailer, brake operating mechanism including two parts, one of which is connected to the brakes and the second of which is separate from the first and movable into and out of holding position as regards the first part, 120

a trip device arranged to contact with the second part for effecting movement of the said second part into holding position as regards the first part upon relative movement between the tractor and trailer during the disconnecting action to hold the brakes applied while the semi-trailer is disconnected from

the tractor, said movable part being movable to non-holding position upon relative movement between the tractor and trailer during connection. ¹⁰

In testimony whereof I have hereunto affixed my signature.

CHARLES H. LAND, JR.
